UNITED STATES PATENT OFFICE.

DAVID L. LINDQUIST, OF YONKERS, NEW YORK, ASSIGNOR TO OTIS ELEVATOR COMPANY, OF NEW YORK, N. Y., A CORPORATION OF NEW JERSEY.

ELECTRICAL CONTROLLING APPARATUS.

1,156,415.

Specification of Letters Patent.

Patented Oct. 12, 1915.

Application filed July 31, 1912. Serial No. 712,508.

To all whom it may concern:

Be it known that I, DAVID L. LINDQUIST, a subject of the King of Sweden, residing at Yonkers, in the county of Westchester 5 and State of New York, have invented a new and useful Improvement in Electrical Controlling Apparatus, of which the following is a specification.

My invention relates to electric motor controlling apparatus particularly adapted for use in connection with furnace hoists.

An object of the invention is to provide controlling means which will operate automatically gradually to slow down the skip 15 or loaded bucket as it nears the mouth of the furnace and stop the same thereat, and which will also operate to effect a quick slowing down and stopping of the bucket at the lower limit of its travel.

In the practical operation of single skip furnace hoists difficulty has been experienced in the control of the motor owing to the wide variation between the conditions of stopping at the upper and lower limits of 20 travel. It is desirable that the load be carried upward as rapidly as possible, but as it approaches the furnace the speed must be gradually and smoothly reduced. In order to prevent swinging of the loaded bucket 25 the slowing down must take place slowly and gradually; the slowing down taking place through a rather long range, and the load must be brought nearly to rest before the brake is finally applied. On the other 30 hand, the bucket as it nears its lower limit of travel may be quickly slowed down and stopped, the slowing down taking place through a short range of travel only in order to economize time. The brake may 35 also be applied before the speed of the bucket has been reduced to the same extent as when loaded. Moreover, the great difference in weight between the empty and loaded bucket has a material influence on 40 the operation of the slowing down apparatus.

The present invention relates to controlling mechanism adapted to meet the above conditions and requirements, and to secure a 45 satisfactory slowing down and stopping of the load carrying device during both its upward and downward travel.

The invention comprehends the use of a single magnet to control the slow down in 50 both directions, together with means to

modify the operation of the magnet or otherwise modify the operation of the slowing down mechanism in one direction of travel, so as satisfactorily to fulfil the requirements of furnace hoist practice. Such 60 magnet may be divided into a number of sections or magnets, to effect a greater refinement of control, all of said sections or magnets being brought into operation during a single slowing down operation. 65

In the accompanying drawings which illustrate an embodiment of my invention, Figure 1 is an elevation view of a single skip furnace hoist to which my invention is applied; Fig. 2 is a diagrammatic illustration of the electrical controlling apparatus; Figs. 3 and 4 are fragmentary views showing modifications of the controlling means.

Referring to Fig. 1, the blast furnace A is supplied with ore and fuel by means of a 75 bucket B connected to a carriage or skip D. The skip is adapted to travel in tracks built on the inclined runway F. The tracks at both the top and bottom of the runway are curved toward a horizontal position. 80 The skip D is operated by a cable G connected at one end to the skip and extended over a direction sheave H at the top of the runway. From the sheave H the cable extends downward to a direction sheave I in 85 the powerhouse K, and from thence to an electric motor M. When the motor runs in one direction, the loaded bucket is carried up and along the tracks and as it nears the upper end of the runway the speed is 90 gradually reduced and the bucket finally allowed to seat on the top of the furnace and discharge its contents. The motor is then run in the reverse direction and the emptied bucket quickly lowered and rapidly 95 brought to rest at the bottom of the run.

The electric controlling apparatus for the motor as shown diagrammatically in Fig. 2, comprising reversing switches R, R', an accelerating magnet L, sectional starting 100 resistance 10, a series field coil 20, a shunt field coil 30, and an electromagnetically controlled brake J, all of which may be of usual or well known construction. The controlling apparatus also comprises the automatic 105 controller C, geared to the motor as above noted, a manual switch E, an extra field winding 40, sectional resistance 50, in circuit with the extra field winding, electro- 110 magnets 60 and 70, automatically control-

ling and varying said resistance in accordance with the speed of the motor, resistances x , x' , x^2 , to modify the operation of the magnets 60, 70, and a relay magnet N controlling the extra field circuit. The mains, designated + and -, respectively, are connected to any suitable source of current supply.

The controller C, as diagrammatically illustrated, comprises a series of concentric rings consisting of segmental contacts and insulating segments. The controller makes substantially a half revolution during the operation of the motor in each direction.

15 To start the motor in the direction to lift the load, the switch E is moved to the left until the contact 11 which is made in one piece and insulated from the arm of switch E engages the stationary contact 12. This 20 completes a circuit for the magnet of reversing switch R, as follows: from the positive main, through conductor 13, magnet coil 14 of reversing switch R, conductor 15, stationary contact 16, segment 17 of the automatic controller, contact 18, wire 19, contacts 12, 11 of the switch E, and conductor 21, to the negative main.

The magnet 14 being energized operates the reversing switch R, and establishes a 30 circuit for the armature M of the motor. This circuit may be traced from the positive main, through the contacts 22, 23, of the reversing switch R, lower contacts 24, of reversing switch R', conductor 25, contacts 35 26, 27 of reversing switch R, conductor 28, motor armature M, conductor 29, contacts 31, conductor 32, starting resistance 10, series field coil 20, to the negative main. The shunt field circuit is also established by way 40 of the reversing switch contacts 22, 23, and conductor 33. A circuit for the brake J may also be traced from the positive main, through contacts 22, 23, 34 of the reversing switch R, conductor 35, brake magnet winding 36, and conductor 21 to the minus main. Owing to the current through the circuits just traced, the brake is lifted and the motor receives a starting current which is limited by the starting resistance. The closure of 50 the reversing switch also establishes a circuit for the accelerating magnet L connected across the brushes of the motor. This circuit may be traced from the brush 41, through conductor 28, reversing switch contacts 27, 55 26, conductor 25, contacts 24, conductor 33, contacts 23, 34, conductor 35, coil of magnet L, a section of the starting resistance 10, wire 32, contacts 31, and wire 29 to the armature brush 42. The extra field 40, the 60 series field 20 and shunt field 30, all being energized, a powerful magnetic field is produced and the starting resistance also being in circuit with the armature, the latter runs at slow speed until the switch E has been 65 moved far enough to connect the contacts 11

and 51. With the switch E in this position, a circuit is completed through the relay magnet N, as follows: From the positive main, through reversing switch contacts 22, 23, 34, conductor 35, coil of magnet N, conductor 52, controller contacts 53, 54, 55, conductor 56, switch contacts 51, 11, and conductor 21 to the negative main. The magnet N being energized, lifts its core and separates the contacts 46, 47, thereby opening the extra field circuit, weakening the motor field and permitting the motor to accelerate to full normal speed. The accelerating magnet being connected across the motor brushes operates in a well known manner to successively short circuit the sections of starting resistance 10, and series field 20, to bring the motor up to full normal speed. As the load carrying device moves upward, the automatic controller C rotates in a counter-clockwise direction. The motor runs at normal speed until the insulating section 57 of the controller runs under the contact 55 and breaks the circuit through the relay magnet N. The latter then drops its core and again completes the extra field circuit through the resistance 50 and field winding 40. The motor field being thus strengthened the speed is reduced. Shortly after the extra field circuit has been completed, circuits 95 are established in succession for the magnets 60 and 70, which control the resistance 50. The circuits for these magnets are in parallel with the motor and are controlled by the inner ring of the automatic controller C. Said ring comprises an insulating section 58 and a contact segment 59. The circuit for the magnet 60 may be traced from the motor brush 42 through the winding of magnet 60, conductor 61, contacts 62 and 59, conductor 63, switch contacts 64, 65, conductor 66, to the motor brush 41. The circuit for the magnet 70 is likewise traced from the motor brush 42, through the coil of magnet 70, conductor 67, controller contacts 68, 59, conductor 68, contacts 64, 65, and conductor 66. After the extra field circuit has been established as above set forth, the circuit for the magnet 60 is completed by the controller contact 59 running under the contact 62, thereby energizing the magnet 60 and causing it to short circuit a number of sections of the resistance 50, depending on the speed of the motor. If the speed is comparatively high, the magnet 60 will be energized to a corresponding degree and a relatively large proportion of the resistance will be shortly short-circuited. This correspondingly strengthens the extra field and produces a greater retarding effect. In other words the magnet 60 operates automatically to counteract any material variations in speed due to load variations, and this effects a uniform slowing down of the motor. Shortly after the magnet 60 has operated, 130

the circuit for the magnet 70 is completed through the controller contacts 68 and 59 so that said magnet operates to further reduce the resistance 50 and effect a corresponding further reduction in the speed of the motor. By this time, the load carrying device has almost reached the limit of travel and has been gradually and smoothly slowed down so that it is moving very slowly. The circuit for the reversing switch magnet is now interrupted by the insulating segment 71 running under the contact 16. The reversing switch R is therefore opened, the current supply cut off from the motor, and the brake J applied to bring the apparatus to rest.

After the load has been discharged into the furnace the switch E is moved to the right to reverse the motor. In this instance the circuit is completed through the reversing switch R' and the connection between the motor armature and mains is thus reversed. The starting and acceleration of the motor on a downward movement of the load device is substantially the same as explained for the upward travel. As the empty bucket or skip nears its lower limit the circuit for the relay magnet N is again interrupted, this time at the contact 72. The circuits for the magnets 60 and 70 are, during the downward travel, completed through resistances x , x' and x^2 . A circuit for the magnet 60 extends through the resistance x , contacts 73, 74, conductor 75, resistance x^2 , contacts 64', 65, and conductor 66. The circuit for the magnet 70 extends through the resistance x' , contacts 76, 74, conductor 75, resistance x^2 , contacts 64', 65, and conductor 66. Owing to the resistances x , x' and x^2 , the magnets 60 and 70 will be weaker for a given motor speed than during the upward travel. As a result a smaller amount of the resistance 50 is short-circuited and the extra field remains comparatively weak so that the motor speed is not reduced to the same extent as when the resistances are omitted from the controlling magnet circuits. In other words during the slowing down of the empty car the brake J is applied while the speed is comparatively high. In order to secure the quick slowing down and stopping of the empty bucket, the contacts of the automatic controller C are arranged so that the circuit for the relay magnet N is only broken shortly before the bucket reaches its downward limit. The contacts 73 and 76 controlling the magnets 60 and 70 are arranged to complete their circuits very shortly after the magnet N operates and in quick succession. The circuit through the reversing switch R' is also broken almost immediately after the magnets 60 and 70 have operated. It will be understood that any one of the resistances x , x' and x^2 may be used alone or that any one of said resistances may be omitted and the other two used together, depending on the specific results desired in any particular case. The resistances may also be varied to secure any desired variation or refinement in the operation of the slowing down magnets. It will be apparent that by the use of the resistances x , x' , x^2 and a proper adjustment of the automatic controller contacts a very quick slowing down and stopping of the empty car may be effected, and also the loaded car may be slowed down very gradually and smoothly. The auxiliary switch 65, operated by the manual switch E, is automatically reversed when the switch E is operated, so that the circuits for the magnets 60 and 70 are completed through the resistances only during the downward travel of the skip.

When the reversing switches are opened a dynamic circuit across the motor armature is established through a resistance 77. This circuit may be traced from the brush 41, through conductor 28, resistance 77, conductor 25, contacts 78, conductor 79, contacts 31, and conductor 29, to the brush 42. This circuit assists in slowing down the motor.

Fig. 3 illustrates a modification in which an extra resistance 80 is placed in the extra field circuit in series with the resistance 50. Conductors 83 and 84 extending from the opposite terminals of the resistance 80 are connected to switch contacts 81 and 82, the contact 81 being carried by the core of an electro-magnet P. In circuit with the electromagnet P are switch contacts 91 and 92, the contact 91 being carried by the switch E, so that when the said switch is moved to the left to cause an upward travel of the load device, the circuit for the magnet will be completed and the contacts 81 and 82 brought together to short circuit the resistance 80. The slowing down operation will therefore be the same as above described in connection with Fig. 2. When the switch E is moved to the right, the contacts 91 and 92 are separated thereby introducing the resistance 80 into the extra field circuit. The field 40 will therefore remain comparatively weak, the result being substantially the same as that obtained by use of the resistances x , x' , x^2 , Fig. 2.

Fig. 4 illustrates a further modification, in which a variable resistance 85 is connected in parallel with a portion or all of the resistances 50. The circuit for the resistance 85 is controlled by a relay magnet P'. The circuit for the magnet P' is controlled by a contact ring 86 of the controller C. In the slowing down operation during the upward travel of the load, the magnet circuit is open at the insulating strip 87 and the circuit through the resistance 85 remains open. During the downward travel, however, the circuit through the resistance 85 is completed and being in parallel with the resistance 50, the total resistance through the

extra field circuit is reduced with a consequent strengthening of the motor field. The result is a comparatively quick slowing down of the motor, so that the empty bucket 5 may be quickly stopped.

It should be noted that with the present invention as embodied in the various arrangements above described, the same magnets 60 and 70 control the slowing 10 down of the load device in both directions of travel and at the same time the rate of slowing down, and the time required to bring the load device to a stop, may be independently regulated and adjusted to meet the practical 15 requirements of furnace hoisting mechanism. It will be understood that various modifications other than those herein disclosed might be made without departing from the spirit and scope of my invention.

20 What I claim is:—

1. In hoisting apparatus, the combination of an electric motor, an extra field circuit, resistance in said circuit, an electro-responsive device operating at a certain power to 25 vary said resistance during the slowing down of the motor in one direction, and means to modify the power of said device and effect a different rate of slowing down in the reverse direction.

30 2. The combination of an electric motor, a load carrying device, an extra field circuit for the motor comprising sectional resistance, an electromagnet connected in a circuit across the motor and controlling said 35 resistance, and means for introducing resistance in the magnet circuit when the motor operates in one direction and for completing a circuit to said magnet independent of the resistance when the motor operates in 40 the opposite direction.

35 3. The combination of an electric motor, a load carrying device, slow down apparatus comprising an extra field circuit in shunt to the motor and sectional resistance in said 45 circuit, an electromagnet connected in a circuit in shunt to the motor and controlling said resistance, a resistance in the electromagnet circuit as the load carrying device is moved in one direction, and means to complete a circuit to said magnet independent 50 of said resistance as the load carrying device is moved in the other direction.

4. In hoisting mechanism, the combination 55 of an electric motor, a load carrying device, reversing switches, slow down apparatus comprising an extra field circuit, resistance in said circuit, an electromagnet adapted to be connected in parallel with the motor armature and controlling said 60 resistance, a resistance for the electromagnet circuit, and an automatic controller comprising means to establish a circuit through the said electromagnet and its resistance as the load carrying device approaches one limit of travel and to complete the magnet circuit in- 65

dependently of the resistance as the load carrying device approaches its limit of travel in the reverse direction.

5. In hoisting mechanism, the combination 70 of a motor, apparatus operated thereby, slow down mechanism comprising an electro responsive device controlling the slowing down of said apparatus at different periods in its operation, and means to automatically vary the power of said electro responsive device and thereby effect different 75 rates of slowing down for different periods of operation.

6. In hoisting apparatus, the combination 80 of an electric motor, a load carrying device raised and lowered by the motor, an electro-responsive device for slowing down the motor at predetermined points for both direction of travel of the load carrying device, and means for subjecting said electro responsive device to the full counter-electro motive force of the motor when slowing down in one direction and for subjecting said device to less than the full counter-electro motive force when slowing down in 90 the other direction.

7. In a system of electric motor control, the combination of an electric motor, speed reduction mechanism operable automatically to effect a predetermined reduction of speed 95 under varying conditions of load on the motor, and means automatically to modify the operation of said speed reduction mechanism.

8. The combination of an electric motor, 100 speed reduction means automatically to produce a retarding action on the motor varying with the motor speed, and means automatically to modify the action of said retarding means and thereby effect a different 105 rate of speed reduction.

9. The combination of an electric motor, means for automatically reducing the motor speed in proportion to the load on the motor, and means for modifying the operation of said speed reducing means for 110 effecting a different rate in the speed reduction also in proportion to the load on the motor.

10. In a system of motor control, the combination of an electric motor, controlling mechanism comprising resistances in circuits of the motor, means operable during the normal slowing down of the motor to automatically vary said resistance in response 115 to variation of the motor speed, and mechanism to effect a modified operation of said resistance varying means under other conditions of slowing down of the motor.

11. The combination of an electric motor, 120 controlling mechanism comprising a variable resistance, an electromagnet controlling said resistance, means to connect said electromagnet to the motor armature to receive current in proportion to the speed of the 125 130

motor, and means to modify the operation of the electromagnet by introducing resistance in circuit therewith.

12. The combination of an electric motor, controlling mechanism therefor comprising a load magnet, resistance controlled thereby, a manual controller, means to establish a circuit for the load magnet when said controller is operated, resistance in said magnet circuit, and means to establish a circuit

through the load magnet independently of said resistance.

In testimony wherof, I have signed my name to this specification in the presence of two subscribing witnesses.
